UNITED STATES PATENT OFFICE.

ROBERT STIRLING, JR., OF EAST CHICAGO, INDIANA.

DESIGN FOR A NIPPLE ATTACHMENT FOR AUTOMOBILE-RADIATORS.

58,952.

Specification for Design.

Patented Sept. 6, 1921.

Application filed May 9, 1921. Serial No. 468,178. Term of patent 14 years.

To all whom it may concern:

Be it known that I, ROBERT STIRLING, Jr., a citizen of the United States, residing at East Chicago, in the county of Lake and State of Indiana, have invented a new, original, and ornamental Design for Nipple Attachments for Automobile-Radiators, comprising a holder for a temperature indicator and an intake for cooling liquid, of which the following is a specification, refer-

ence being had to the accompanying drawing, forming part thereof.

Figure 1 is a perspective view of a nipple attachment for automobile radiators showing my new design.

Fig. 2 is a side elevation.

I claim:

The ornamental design for a nipple attachment for automobile radiators, as shown.
